UNITED STATES PATENT OFFICE.

WALLACE H. CAMP, OF WATERBURY, CONNECTICUT, ASSIGNOR OF ONE-HALF TO BUSHROD H. CAMP, OF BOSTON, MASSACHUSETTS.

DESIGN FOR A POST-OFFICE LOCK-BOX DOOR.

SPECIFICATION forming part of Design No. 13,982, dated June 19, 1883.

Application filed March 30, 1883. Term of patent 7 years.

To all whom it may concern:

Be it known that I, WALLACE H. CAMP, a citizen of the United States, residing at Waterbury, in the county of New Haven and State 5 of Connecticut, have invented certain new and useful Improvements in Designs for Post-Office Lock-Box Doors; and I do hereby declare the following to be a full, clear, and exact description of the invention, such as will enable others skilled in the art to which it appertains to 10 make and use the same.

The accompanying drawing, forming part of this specification, shows an elevation of my improvement.

15 Heretofore doors for post-office lock-boxes have been made very plain, or in front of the glass were metal bars crossed so as to form diamond-shaped apertures; and, also, scroll-work has been extended from the frame of the door 20 in front of the glass center; also, the numbers of the boxes have been painted on the glass, or paper numbers have been pasted on the same, but they are liable to get wiped off in cleaning the glass.

25 The leading features of my design are the ornamental work in the frame of the door, extending around the entire margin, as well as the lock-escutcheon, the plain open glass center with the box-numbers therein, and the letters between the escutcheon and the sides of 30 the door.

A is the plain open glass center, set within the frame B and with number C therein, as shown.

C is the ornamental work in the margin of

the frame; and it consists of straight and curved 35 lines which join and cross each other in the manner shown, creating figures of different shape and size.

I do not wish to confine myself to the exact style of ornamentation shown, as the effect 40 presented to the eye by my improved design may be varied to a slight extent without departing from the spirit of my invention.

The position of the letters "U. S.," the number of the box, and the lock being no part of the 45 design itself, it is apparent that their position is not material to the same, but may be varied without departing from the spirit of my invention.

Having thus described my invention, what I 50 claim as new, and desire to secure by Letters Patent, is—

1. The design for a post-office lock-box door, substantially as shown in the accompanying drawing.

2. The design for a post-office lock-box door herein shown and described, the same consisting of the open center and margin of straight and curved lines joining and crossing each other, thereby forming figures of different shape 55 and size.

In testimony whereof I affix my signature in presence of two witnesses.

WALLACE H. CAMP.

Witnesses:

HENRY A. BISHOP,
W. T. HAVILAND.
